(57) **CLAIM**

(21) Appl. No.: **29/491,206**

The ornamental design for a golf putter head with self-adjusting face, as shown and described.

(22) Filed: **May 19, 2014**

DESCRIPTION

(51) **LOC (10) Cl.** **21-02**

FIG. 1 is a perspective view of a golf putter head with self-adjusting face embodying my design;

(52) **U.S. Cl.**

FIG. 2 is a front view of the golf putter head with self-adjusting face;

USPC **D21/742**

FIG. 3 is a rear view of the golf putter head with self-adjusting face;

(58) **Field of Classification Search**

FIG. 4 is a right side view of the golf putter head with self-adjusting face;

USPC D21/736-746; 473/324-331, 343-346
See application file for complete search history.

FIG. 5 is a left side view of the golf putter head with self-adjusting face;

(56) **References Cited**

FIG. 6 is a top view of the golf putter head with self-adjusting face; and,

U.S. PATENT DOCUMENTS

FIG. 7 is a bottom view of the golf putter head with self-adjusting face.
